Primary Examiner — Kelley A Donnelly(74) *Attorney, Agent, or Firm* — Sterne, Kessler, Goldstein & Fox P.L.L.C.(57) **CLAIM**

The ornamental design for a retail display, as shown and described.

DESCRIPTION

FIG. 1 is a top front perspective view of a retail display showing the claimed design;

FIG. 2 is a bottom front perspective view thereof; and,

FIG. 3 is a front view thereof.

The broken lines in the figures show portions of the retail display or environment that form no part of the claimed design.
